SINGLE HOLDING LINK WOOD FRAME TO METAL FOLDING BED

Robert Goodman, Philadelphia, Pa.

Application December 31, 1954, Serial No. 479,099

2 Claims. (Cl. 5—13)

My invention relates to davenport-beds, and more particularly, relates to folding and positioning means to position the bed portion in space relationship to the davenport.

In davenport-bed combinations, it is essential that the folding and unfolding of the bed portion be accomplished in a manner that permits easy and complete control of the bed portion in all positions from the fully compacted arrangement of the bed within the davenport to the fully extended arrangement of the bed portion. In all positions of the operation, it is essential that the bed be supported and balanced and that little effort is required on the part of the operator, as this type bed is often operated by women or small children. It is also essential that the movement of the bed portion be accomplished without jamming, and that the bed portion be so constructed that all the sections of the bed portion be in definite relative position to each other and to the davenport throughout all phases of the folding and unfolding operation.

It is, therefore, an object of my invention to construct a bed spring supporting means for a davenport-bed that can be folded into a compacted arrangement within a davenport of average size; the davenport having a seat and back positioned to comfortably support a person seated on the davenport.

Another object of my invention is to construct a bed spring supporting means for a davenport-bed that has all its members in almost perfect balance in all positions during the folding and unfolding operation.

Another object of my invention is to devise a bed spring supporting means for a davenport-bed that has all its members positioned in definite space relationship to each other and to the davenport in all phases of the folding and unfolding operation.

Another object of my invention is to devise a bed spring supporting means for a davenport-bed that is firm and rigid in its extended arrangement to provide a firm support for the mattress of the bed.

Another object of my invention is to devise a bed spring supporting means for a davenport-bed that provides a firm and rigid support for the seat of the davenport when the bed spring supporting means is completely compacted within the davenport.

Other objects of my invention are to provide an improved device of the character described, that is easily and economically produced, which is sturdy in construction, and which is highly effective in operation.

With the above and related objects in view, my invention consists in the details of construction and combination of parts, as will be more fully understood from the following description, when read in conjunction with the accompanying drawings, in which:

Fig. 1 is a perspective view of a davenport-bed embodying the features of my invention.

Fig. 2 is a sectional elevational view of the davenport-bed taken along line 2—2 of Fig. 1, showing the bed spring supporting means in its fully compacted arrange-

2

ment; the supported mattress is shown in dot and dash lines.

Fig. 3 is a sectional elevational view of the davenport-bed with the bed portion partially withdrawn from the davenport.

Fig. 4 is a fragmental sectional elevational view of the bed spring supporting means as it would appear after the first unfolding operation.

Fig. 5 is a fragmental sectional elevational view of the bed spring supporting means as it would appear with the foot section of the support frame in a vertical position.

Fig. 6 is a fragmental sectional elevational view of the bed spring supporting means in its fully extended arrangement.

Referring now in greater detail to the drawings, I disclose a davenport-bed, generally designated D, arranged to house a folded bed frame, generally designated B. The davenport is comprised of an upholstery-covered frame, generally designated F, with the folded bed frame B supporting an upholstered seat, generally designated S. The foldable bed spring supporting frame B is the feature of my invention, and the frame B is comprised of a head section, generally designated H, an intermediate section, generally designated I, a folding section, generally designated FS, and a foot or end section, generally designated E. In describing the functioning of the bed frame, the operation of the parts on the left hand side of the bed frame B will be described. However, it is to be understood that the corresponding parts on the right hand side of the bed frame function in a similar manner.

A mounting plate 10, securely attached to the davenport frame members F1 and F2, is provided with a pivot P1 to which is pivotally attached a head section positioning link 11. Adjacent to the outer end of the head section positioning link 11 is a pivot P2 that pivotally connects the link 11 and the bed frame head section H. The head section H of the bed frame B is comprised of parallel members 12 and a transverse spreader member 13. The parallel members 12 and the transverse spreader member 13 are provided with inwardly extending legs 12A and 13B respectively, to which the bed spring (not shown) is attached. The lower ends of the parallel members 12 of the head section H of the bed frame B are pivotally attached at P3 to parallel members 14 of the intermediate section I of the bed frame B. A head section restraining link 15 is provided to keep the head section positioning link 11 and the parallel members 12 of the head section H acute angularly disposed to each other through the initial movements of the bed frame B as it is being withdrawn from the davenport D (see Figs. 1 and 2). The upper end of the head section restraining link 15 is pivotally attached to the outer end of the head section positioning link 11 at P4. The lower end of the head section restraining link 15 is pivotally attached at P5 to an L lock upper operating link 16, hereinafter described. The inner end of the L lock upper operating link is pivotally attached to the head section parallel member 12 at P8. From the illustrations, Figs. 2, 3, and 6, it will be observed that the head section restraining link 15 controls the angular displacement between the head section positioning link 11 and the parallel members 12 of the head section, retaining the link 11 and member 12 in controlled angular displacement (Figs. 2 and 3) until the parallel members 12 of the head section H and the parallel members 14 of the intermediate section I approach a parallel position as shown in Figs. 4 and 5.

A spring securing plate 17 is pivotally attached at P6 to the head section positioning link 11. Securely attached to the spring securing plate 17 are dual helical tension springs 18A and 18B. The lower ends of the

tension springs 18A and 18B are securely attached to an outwardly extending arm 10A on the lower portion of the mounting plate 10. The springs exert downward force on the link 11 and assist in the balancing and in the movement of the bed frame B out of and into the davenport frame F.

A locking means is provided to secure the folded portions of the bed frame B when the bed frame is compacted within the davenport frame F. The locking means is comprised of an L shaped locking unit 20 that is positioned and actuated by the relative positions of the head section H, the intermediate section I, and the folding section FS of the bed frame B. The upper portion of the L shaped locking unit 20 is pivotally attached to the outer end of the L lock upper operating link 16 at P7. In the fully compacted position of the bed frame B, the L lock upper operating link holds the upper portion of the L shaped lock unit 20 forward and secure over an outwardly extending boss 21 located on the lower end of a locking bar 22 (Fig. 2). Also, in the fully compacted position of the bed frame B, the lower portion of the L-shaped lock unit 20 is held toward the head of the bed frame B by an L lock lower operating link 23, the lower portion of the L shaped lock being pivotally attached at P9 to the inner end of the link 23; the outer end of the link 23 is pivotally attached to the parallel member 24 of the bed frame folding section FS at P14. As the L shaped locking unit 20 is located on the outerside of the parallel member 14 of the intermediate section I and the L lock lower operating link 23 is located on the inner side of the parallel member 14, the pivot connection P9 is arranged to operate through a slot 25 in the parallel member 14. This slot performs the dual function of permitting backward and forward movement of the lower portion of the L shaped locking unit 20 by the L lock lower operating link 23, as described above, and it also limits the backward movement of the L lock lower operating link 23 to position the folding section FS of the bed frame B, to which the folding section FS is pivotally attached at P10, at right angles to the intermediate section I of the bed frame during folding of the bed frame B. The parallel members 14 of the intermediate section I are provided with inwardly extending legs 14A to which the bed spring (not shown) is attached.

Parallel members 24 of the folding section FS of the bed frame B are pivotally attached to the parallel members 14 of the intermediate section I at P10. The folding section FS is definitely positioned at right angles to the intermediate section I when the bed frame B is in the partly or fully compacted condition (see Figs. 2 and 3), by the L lock lower operating link 23, as described above. The same link 23 functions to hold the parallel units 24 and 14 in parallel alignment when the bed frame B is partly or fully extended (see Figs. 5 and 6). This is accomplished by arranging the L lock lower operating link to pass beyond the pivot point P10 when the bed frame is extended. Inwardly extending legs 24A on the parallel members 24 are provided for attachment of a bed spring (not shown).

Parallel members 26 of the end section E of the bed frame B are pivotally attached at P11 to the parallel members 24 of the folding section FS of the bed frame. The outer ends of the parallel members 26 are spaced by a spreader tube 27. The bed spring (not shown) is secured to inwardly extending legs 26A of the parallel members 26 and to the tubular spreader 27 of the bed frame. Pivotedly attached at P12 to the parallel member 26 is a locking bar 22, as mentioned above. This locking bar 22 performs the dual function of positioning an integral boss 21 that is secured by the L shaped locking unit 20, as described above, to secure the bed frame B when it is in a compacted condition, and to definitely position the intermediate I and end E sections of the bed frame in parallel arrangement when the bed frame B is

in its fully compacted condition. This parallel arrangement is accomplished by having the integral boss 21 on the locking bar 22 arranged to impinge on the upper edge of the parallel member 14 of the intermediate section I when the bed frame is in a compacted condition. When the bed frame is in a partly or completely compacted condition, the locking bar 22 is positioned at right angles to the parallel members 26 of the end section E of the bed frame B (see Figs. 2, 3, and 4). However, when the end section E moves from the vertical position shown in Fig. 5 to a horizontal position shown in Fig. 6, a locking bar operating link 28, which is pivotally attached to the locking bar 22 at P13 and to the parallel member 24 at P14, functions to fold the locking bar to a position almost parallel to the parallel member 26 (see Fig. 6). This folding of the locking means is an important feature of my invention, for it eliminates all projections above the bed frame that would tend to injure the user of the davenport bed. The locking bar operating link also extends across the pivot point P11 to provide rigidity to the bed frame when the bed frame B is in the fully extended position.

To insure ease of operation and definite positioning of the bed frame B as it moves out of or into the davenport frame F, a combination of positioning links are provided (see Fig. 3). The positioning links are comprised of an L shaped support link 30 that is pivotally attached to the bed frame at P26. The lower end of the L shaped support link 30 is pivotally attached at P15 to a short positioning link 31 and at a point adjacent to the lower end, the positioning link 30 is pivotally attached at P16 to a long positioning link 32. The fixed end of the short positioning link 31 is pivotally attached at P17 to a positioning link mounting plate 33. The fixed end of the long positioning link 32 is pivotally attached at P18 to the positioning link mounting plate 33. It will be observed from the illustrations (see Figs. 2, 3, and 4), that the positioning links 31 and 32 position the L shaped support link 30 so that the bed frame B, supported at P26, moves through an arcuate path in its movement out of and into the davenport frame F. The L shaped supporting link 30 changes its position as the bed frame B moves out of the davenport frame F. The upper portion 30A, acting through a leg positioning link 34, moves an intermediate section supporting leg 35, pivotally connected to the parallel member 14 of the intermediate section I of the bed frame B, into position so that when the bed frame B is partly extended (see Fig. 3), or fully extended (see Fig. 6), it will substantially be supported. The leg positioning link 34 is pivotally attached to the L shaped link 30 at P19 and to intermediate section support leg 35 at P20. When the bed frame B is being moved into the davenport frame, the L shaped support link 30 and leg positioning link 34 fold the intermediate section support leg 35 so that when the bed frame is in its fully compacted condition within the bed frame F, the intermediate section support leg 35 lies parallel with the parallel member 14 of the intermediate section. A helical tension spring 37 pivotally attached at P21 to the positioning link 60 mounting plate 33 and to the L shaped support link 30 at P26 by way of the connecting link 38 is provided to assist the operator in the movement of the bed frame B out of and into the davenport frame. The tension on and position of the helical tension spring 37 tends to the weight of the bed frame B in its various positions as it moves into or out of the davenport frame B. A spreader bar 36 is fixedly attached to the intermediate section support legs 34. This spreader bar 36 adds rigidity to the bed frame F and reacts against the bed spring (not shown) that is attached to and supported by the bed frame B.

The davenport seat assembly is attached to and supported by the folding section FS and the end section E of the bed frame when the bed frame is fully compacted (see Fig. 2), and fully extended (see Fig. 6). When the bed

frame B is fully compacted within the davenport frame F, the bed frame forms a substantial support for the davenport seat and the persons that may be seated thereon. Also, when the bed frame B is fully compacted within the davenport frame F and securely locked by the locking bar 22 and integral boss 21 interfitting with the L shaped locking unit 20, there is no false movement of the davenport seat S that would tend to annoy the occupants of the davenport while they are seated or when they rise from the davenport. When the bed frame is in the fully extended position (see Fig. 6), the davenport seat S is suspended beneath the bed frame B, out of the way. The davenport seat assembly S is supported and suspended at its front end by a Z shaped support 40 which is pivotally attached at P22 to the folding section parallel members 24 of the bed frame and fixedly attached to the seat assembly front spreader angle 41 at 42. Parallel side members 43 of the seat assembly are fixedly attached at the ends of the spreader angle 41 and pivotally attached at P23 to the bed frame end section support legs 44. The end section support legs 44 are pivotally attached to the parallel members 26 of the bed frame end section E at P24. When the bed frame is being extended (Figs. 5 and 6), the seat assembly S acting as a rigid link between the pivot P22 and the pivot P23 causing the end section support leg 44 to assume a vertical position to support the end section E of the bed frame F (see Fig. 6).

When the bed frame B is being folded, the reverse of the operations described above takes place until the bed is fully compacted within the davenport frame and the davenport seat is in position for use as illustrated in Fig. 2.

Although my invention has been described in considerable detail, such description is intended as being illustrative rather than limiting, since the invention may be variously embodied, and the scope of the invention is to be determined as claimed.

I claim as my invention:

1. A foldable bed frame for a sofa bed comprising head, body, folding section and foot sections pivotally connected in end to end relationship and adapted to be forwardly unfolded to a bed position wherein the sections are arranged in substantial coplanar relationship with the head and foot sections at the ends of the bed, the body section adjacent the head section, said folding section adjacent the foot section and being adapted to be rearwardly folded to a seat position wherein the foot section forms a seat cushion support and is parallel to and spaced above said body section with said head section extending upwardly and at right angles to said body section, a frame, a single head section positioning link connected at one end to said

frame and its other end being connected to the head section of said sofa bed, an L-shaped lock, a head section restraining link having one end pivotally connected to said head section positioning link and its other end connected intermediate the ends of said L-shaped lock upper operating link, a mounting plate pivotally mounted to said head section positioning link, a spring mounted at one end of said mounting plate and its other end mounted to said frame, said spring being located between said head section positioning link and said bed section when said frame is in sofa position, a means to be engaged by said L-shaped lock upper operating link whereby said frame can be held in lock position when it is in sofa position.

2. A foldable bed frame for a sofa bed comprising head, body, folding section and foot sections pivotally connected in end to end relationship and adapted to be forwardly unfolded to a bed position wherein the sections are arranged in substantial coplanar relationship with the head and foot sections at the ends of the bed, the body section adjacent the head section, said folding section adjacent the foot section and being adapted to be rearwardly folded to a seat position wherein the foot section forms a seat cushion support and is parallel to and spaced above said body section with said head section extending upwardly and at right angles to said body section, a head section positioning link, a spring securing plate pivotally mounted to said head section positioning link, a spring having one end connected to said securing plate and the other end connected to the bottom of an outwardly extending arm mounted adjacent the bottom of said davenport, a head section restraining link pivotally connected at one end to said head section positioning link, an upper operating link, said restraining link connected intermediate the ends of said operating link, and L shaped locking unit, one end of said upper operating link connected to said head section and the other end connected to said L shaped locking unit, a locking bar operating link having one end slidably in said body section and carrying one end of said L shaped locking unit, the other end of said locking bar operating link being pivotally mounted to said folding section whereby said L shaped locking unit is compactly positioned adjacent said body section when said davenport is opened.
